REVOLVING-RING-HEARTH OVEN

Application filed June 2, 1926, Serial No. 113,288, and in Germany June 3, 1925.

As is known, a revolving ring hearth oven consists of an annular muffle the lower opening of which is closed by a revolving ring forming the hearth onto which the oven material is charged, mostly in the form of a thin layer. Some difficulty is encountered in the sealing of the oven chamber against the outside which is necessary in order, on the one hand, to avoid losses of heat and, on the other, to protect the supporting and driving means of the hearth against the effect of the heat. This problem which, in itself, is difficult of solution is, however, increased if heating from below, which is highly desirable, is to be resorted to.

The object of this invention is a simple and inexpensive solution of this problem.

In its solution, it is to be borne in mind that the ring hearth, usually constituted by a single plate, has to fulfil a double function, i. e. on the one hand, heat insulation against the outside and, on the other, the carrying of the charge and the heating thereof. While the first function necessitates the construction of the plate from, or its coating with, heat-insulating material and keeping it cool, the second function makes it desirable to produce the plate from heat conductive material and to render it accessible to heat from all sides possible.

From this consideration emanates the fundamental idea of the invention residing in the provision of two separate rings individually performing the respective functions but rigidly connected so as to be driven in unison. This results in the possibility of enabling both plates to be so journaled and made of such substances as to adapt them each to perform its respective work in a completely satisfactory manner.

According to the invention, therefore, the revolving ring hearth oven, heated from below, comprises two superposed ring shaped members connected by appropriate supports so that the lower ring forming the carrier ring, and closing the oven chamber, is provided with the supporting and driving means, while the upper ring, being the working hearth proper, is charged with the material to be treated and is situated above the

lower ring at such a distance as to be heated from below, particularly by radiated heat.

According to the invention, preferably, the lower ring is made of, or coated with, heat insulating material and the upper disc is of heat conductive material. In arrangements in which the working hearth is within the oven, the travelling frame however outside thereof, the inconvenience easily arises that during working the component parts of the oven are not uniformly heated. In the first place the working hearth plate itself, no matter of what material, has the tendency to become deformed by the heat of the oven, particularly if it is rigidly connected to the supporting and travelling structure. The provision of expansion grooves does not attain the object aimed at, firstly, because these grooves become filled with particles of the oven material whereby their effect is defeated and, secondly, because the gas tight-closure of the oven would be affected thereby.

A further characteristic of the invention resides in a hearth arrangement whereby the carrier ring is connected to the hearth ring proper by a connecting structure which permits of relative movement of the hearth ring. This connecting structure may consist of roller members arranged at intervals and transversely of the carrier ring and upon which the working hearth is freely supported. Moreover, the carrier ring is supported by the travelling frame by means of a pivotal connection. This arrangement provides a double link-like connection whereby the hearth arrangement really comprises three constituents, in themselves rigid, i. e. the travelling structure; the carrier ring and the working ring or hearth proper having between them pivotal connections so as to enable relative displacements or swinging movements between the hearth and the travelling structure should the hearth, as a consequence of the heat, be caused to expand differently from the travelling frame work.

In a convenient form, the travelling structure may consist of bogies or trucks rigidly connected by a driving rim and each carrying one of the pivotal connections. Due to this pivotal connection of the travelling

frame with the carrier ring, and the latter with the hearth proper as described, the working hearth and the travelling structure each form a self-contained rigid body and nevertheless, in the event of unequal expansion the hearth, cannot become deformed nor can the travelling frame be readily thrown out of its place and the uniform working on the rail track be caused to suffer.

Since, for the performance of certain oven processes such as drying, dry distillation or gasification of fuels or the like, the material must be treated in the form of a thin layer, large quantities cannot obviously be treated at once. It is therefore of importance to enlarge the surface area of the hearth, if possible. The size of the individual ring plates is limited for practical reasons. Hitherto it was necessary, in order to obtain larger outputs, to arrange several such ovens. This, however, met with the difficulty that the revolving hearth type of oven, owing to its circular shape, occupied much space.

Accordingly, a further feature of the invention resides in an oven arrangement in which this defect is obviated. This is achieved by several ovens being built one within the other so that an oven of a certain diameter concentrically embraces one of smaller diameter. These concentrical oven chambers, arranged in which are likewise concentrically revolving hearths, are by preference arranged within a common brickwork casing. In this way considerable economy is obtained in regard to space while the losses of heat by radiation are minimized.

A further advantage resulting from this oven arrangement resides in the concentrically arranged oven units supplementing one another in so far as they enable the material to be conveyed from the discharge point of one oven directly to the charging point of the next oven. Thus the treatment by heat, to the extent to which it could not be completed in one oven, is continued in the next oven chamber. This possibility can be utilized particularly in multi-phase processes by carrying out one stage in each of the concentrical oven chambers and then conveying the material directly to the next one for the performance of the next stage. The advantages of this treatment may be made use of, for example, in the drying and dry distillation of lignite. If use is made for this purpose of two concentrically arranged oven units of the revolving hearth type, the moist material is first charged onto the hearth of the outer oven and dried. The dried material is then taken from the discharge point of that oven and charged directly to the charging point of the inner oven. In this inner oven, dry distillation sets in and is carried through as this oven is traversed by the material. In such two stage processes, the heat given off by the heating gases leaving the

chamber of the first oven may be also utilized fully in the adjacent oven.

In the example illustrated the dry distillation calls for considerable higher temperature than the drying, thus enabling the heating gases, after traversing the distilling oven, to be introduced directly into the heating chambers of the drying oven.

Several constructional forms of the invention are illustrated in the accompanying drawings in which:

Figure 1 is a partial transverse sectional view, taken on the line 1—1 of Figure 1^a, illustrating the simplest form of the invention.

Figure 1^a is a plan view of the construction shown in Figure 1.

Figure 2 is a view similar to Figure 1, showing a second form of the invention.

Figure 2^a is a section on the line 2—2 of Figure 2.

Figure 3 is a transverse sectional view showing the form of the invention illustrated in Figure 2 embodied in two concentrical oven chambers.

Figure 4 is a somewhat similar view showing in elevation the means of transfer of material from one chamber to another.

In the arrangement shown in Fig. 1 the annular muffle *a*, which is enclosed in the casing *a'*, is surrounded on three sides by a heating flue *b* for direct heating. The oven chamber open at the bottom is closed by the rotary hearth *c*. This hearth, according to this invention comprises a lower ring *e* made, for example, of iron or other metal coated with heat insulating material provided with packing means *e'*, supports *f* and depending flange *g*, to which a suitable driving means such as shown in Fig. 2 can be connected, and an upper ring or hearth proper *d* which is rigidly connected to the ring *e* by suitably spaced transverse support *h*. The ring *d* is located above the ring *e* at a distance calculated in accordance with working conditions. It is thus brought more closely to the heated oven cover whereby the charge spread over it in a thin layer is intensively heated from above. At the same time the upper ring *d* is also heated from below by the radiated heat from the oven walls penetrating the free space between the rings *e* and *d*, simultaneously with heating by the oven gases. By a specially provided current of hot gases between the rings *e* and *d*, the heating may be further increased. If it is desired to operate mainly with heat radiation from below, it may be preferable to make the driving ring *e* smaller than the hearth ring *d*. If then the lateral walls of the muffle are appropriately contracted downwardly, a substantial increase of the heating by radiation is obtained.

An arrangement embodying the latter feature is shown in Figs. 2, 2^a and 3.

The arrangement in Figs. 2 and 2^a shows

generally the features of the oven described with reference to Fig. 1.

The oven arch is supported on annular posts or supports *z* forming between them a space for the accommodation of the travelling structure. The hearth arrangement in the example shown consists of three units rigid in themselves, i. e. the hearth ring *d*, the carrier ring *e* and the travelling frame generally indicated by the character *f*. The latter comprises a driving rim *g* caused to revolve by any appropriate means such as a worm gear *g*². This rim rigidly connects the trucks *k* uniformly distributed circumferentially thereof. Each bogie or truck comprises an axle *i* journaled on which is a set of wheels *k*' travelling on a rail track. Each bearing *l* of each truck *k* receives a pivot pin *l*' transversely to the radius of the oven. These pivot pins form the link-like or pivotal connection between the travelling structure and the hearth ring *e* located above the same. This ring is usually of metal coated with a heat insulating substance and is provided with the packing means *e*' by which the oven chamber *a* is rendered gastight in downward direction. These packing means may consist of sand troughs or liquid seals. Connecting means for the two ring members of the hearth are provided, said means being in the form of spaced supports extending between said ring members and arranged transversely thereof and preferably radially relative to the axis of rotation of the hearths. In constructing said connecting means, the carrier ring carries, distributed over its circumference a number of bearing elements *m*, *m*' which in turn support roller members *n*, *n*' illustrated in Fig. 2^a. In the example shown, these roller members have, for example, the shape of rings made up of angle irons. These rings may be fitted loosely in the bearing elements *m*, *m*' or they may also be fixed thereto if desired. By preference, these rollers are used in pairs embracing radial ribs *o* arranged on the ring hearth *d*. Loosely resting upon each of these roller pairs is an upper bearing block consisting of two separate members *p*, *p*' forming between them a space for a rib *o*. Obviously, this upper bearing block may be constructed in one piece provided with the space for the rib *o*. The revolving hearth ring *d* can then be freely placed on the bearing members *p*, *p*', the result being that the hearth ring is safely engaged by the travelling frame but that nevertheless the three main units may mutually adjust themselves during unequal heating.

The oven shown in Fig. 3 includes two separate revolving ring hearth oven units A and B each of a construction similar to the hearth shown in Fig. 2. The oven unit A has a larger diameter than the oven unit B, the diameters being so dimensioned that the

inner ring wall *a*' of the outer oven coincides with the outer ring wall of the inner oven. The units contain the oven chambers *a* *a* in the form of annular channels which are open at the bottom and are surrounded by heating flues *b* *b*. Arranged in each chamber *a* is a revolving hearth ring *d* supported on a carrier ring *e* which is provided with the means insulating the respective oven chamber from the space below. The revolving ring structure is supported on a travelling frame *f*' which includes the driving means *g*'. Each ring hearth unit may be driven separately or they may be driven in unison.

In order to accomplish the transmission of material and heating gases from one oven unit to another, there is provided the construction shown in Figure 4, wherein the material is fed through the funnel *y* on to the outer or left-hand ring *d*. Above this ring is mounted the suction nozzle *q* which is connected, by the pipe *q*', to the separation chamber *s*. A current of air in the pipe *q*' causes the material to be drawn from said outer ring *d* into the chamber *s* where the dust is separated and passes downwardly through the nozzle *r* on to the inner ring *d* for further treatment in the inner oven chamber. The remaining material in the chamber *s* passes through the pipe *s*' into a blower *t* from which it is conveyed through the pipe *t*' back into the outer oven chamber, thus providing for a complete circulation of the material from one oven chamber to another. To permit the heating gases in the inner or adjacent channels *b*' to flow through the heating chambers of both ovens, said channels are connected by openings *x*, while the outer channels *b* are joined together at the ports *u* and *w* by a pipe *v* through which the gases in said outer channels flow from one oven chamber to another.

What is claimed and desired to be protected by Letters Patent is:—

1. In a revolving ring hearth oven, an annular muffle having an open underside forming an oven chamber, a rotating ring hearth movable in said chamber, said hearth consisting of upper and lower ring members, the latter of which forms a closure for the open underside of said chamber, and the upper ring member being spaced above the lower member a distance sufficient to permit heating thereof from below, connecting means including spaced supports between said upper and lower ring members arranged transversely thereof to permit heat from the side walls of the oven chamber to enter the space between said ring members, said connecting means comprising pivots for joining said ring members, and a supporting and rotating structure beneath said hearth for continuously rotating the same relative to said muffle.

2. In a revolving ring hearth oven, an an-

- 6 nular muffle having an open underside forming an oven chamber, a rotating ring hearth movable in said chamber, said hearth consisting of upper and lower ring members, the latter of which forms a closure for the open underside of said chamber, and the upper ring member being spaced above the lower member a distance sufficient to permit heating thereof from below, connecting means including spaced supports between said upper and lower ring members arranged transversely thereof to permit heat from the side walls of the oven chamber to enter the space between said ring members, said connecting means comprising roller members interposed between said ring members, and a supporting and rotating structure beneath said hearth for continuously rotating the same relative to said muffle.

10 3. In a revolving ring hearth oven, an annular muffle having an open underside forming an oven chamber, a rotating ring hearth movable in said chamber, said hearth consisting of upper and lower ring members, the latter of which forms a closure for the open underside of said chamber, and the upper ring member being spaced above the lower member a distance sufficient to permit heating thereof from below, connecting means including spaced supports between said upper and lower ring members arranged transversely thereof to permit heat from the side walls of the oven chamber to enter the space between said ring members, said connecting means comprising roller members joining said ring members, a supporting and rotating structure beneath said hearth and exteriorly of the oven for continuously rotating said hearth relative to said muffle, and a plurality of pivots connecting said supporting and rotating structure to said lower ring member.

15 4. In a revolving ring hearth oven, an annular muffle having an open underside forming an oven chamber, a rotating ring hearth movable in said chamber, said hearth consisting of upper and lower ring members, the latter of which forms a closure for the open underside of said chamber, and the upper ring member being spaced above the lower member a distance sufficient to permit heating thereof from below, connecting means including spaced supports between said upper and lower ring members arranged transversely thereof to permit heat from the side walls of the oven chamber to enter the space between said ring members, said connecting means comprising roller members joining said ring members, a supporting and rotating structure including a plurality of trucks arranged beneath said hearth exteriorly of the oven for continuously rotating said hearth relative to said muffle, and a pivot carried by each truck and connected to said lower ring member.

20 5. In a revolving ring hearth oven, a plurality of annular oven chambers arranged concentrically one within another, a revolving ring hearth movable in each chamber, each hearth consisting of upper and lower ring members, the latter of which forms a closure for the underside of its respective chamber, and the upper ring member being spaced above the lower ring member to permit heating thereof from below, connecting means including spaced supports between the upper and lower ring members of each hearth arranged transversely thereof to permit heat from the side walls of the oven chamber to enter the space between said ring members, said connecting means comprising pivots for joining said ring members, and means for continuously rotating each hearth relative to its chamber.

25 6. In a revolving ring hearth oven, a plurality of annular oven chambers arranged concentrically one within another, a revolving ring hearth movable in each chamber, each hearth consisting of upper and lower ring members, the latter of which forms a closure for the underside of its respective chamber, and the upper ring member being spaced above the lower ring member to permit heating thereof from below, connecting means including spaced supports between the upper and lower ring members of each hearth arranged transversely thereof to permit heat from the side walls of the oven chamber to enter the space between said ring members, said connecting means comprising pivots for joining said ring members, means for continuously rotating each hearth relative to its chamber, and a casing common to said concentric oven chambers.

30 7. In a revolving ring hearth oven, a plurality of annular oven chambers of different diameters arranged concentrically one within another, a revolving ring hearth in each chamber, and a casing common to and enclosing all of said chambers.

35 8. In a revolving ring hearth oven, a plurality of annular oven chambers of different diameters arranged concentrically one within another, one of said chambers having a discharge point and the other a charging point in communication therewith, a revolving ring hearth in each chamber, and means for transferring the material from the hearth of the first named chamber through said discharge and charging points on to the hearth in the other chamber.

40 9. In a revolving ring hearth oven, a plurality of annular oven chambers of different diameters arranged concentrically one within another, one of said chambers having a discharge point and the other a charging point in communication therewith, said points providing means through which the heating gases from one oven chamber may enter directly into the other oven chamber, a revolving ring hearth in each chamber, and means

for transferring the material from the hearth
of the first named chamber through said dis-
charge and charging points on to the hearth
in the other chamber.

5 In testimony whereof we have signed our
names to this specification.
